UNITED STATES PATENT OFFICE

HARRY KURILLA, OF SHENANDOAH, PENNSYLVANIA

DESIGN FOR AN AUTOMOBILE RADIATOR-CAP ORNAMENT OR SIMILAR ARTICLE

Application filed July 9, 1929. Serial No. 31,975. Term of patent 7 years.

To all whom it may concern:

Be it known that I, HARRY KURILLA, a citizen of the United States, residing at Shenandoah, in the county of Schuylkill and State of Pennsylvania, have invented a new, original, and ornamental Design for an Automobile Radiator-Cap Ornament or Similar Article, of which the following is a specification, reference being had to the accompanying drawing, forming a part thereof, wherein:

Figure 1 is a front view of an automobile radiator cap ornament or similar article showing my new design.

Figure 2 is a view in side elevation of the same.

I claim:—

The ornamental design for an automobile radiator cap ornament or similar article substantially as shown.

HARRY KURILLA.
